UNITED STATES PATENT OFFICE.

HENRY B. COLE, OF LOS ANGELES, CALIFORNIA.

AUTOMATIC STREET-RAILWAY CROSSING.

1,235,113.

Specification of Letters Patent. Patented July 31, 1917.

Application filed August 19, 1916. Serial No. 115,862.

To all whom it may concern:

Be it known that I, HENRY B. COLE, a citizen of the United States, residing at Los Angeles, in the county of Los Angeles and State of California, have invented certain new and useful Improvements in Automatic Street-Railway Crossings, of which the following is a specification, reference being had to the accompanying drawings.

10 This invention relates to railway tracks and particularly to crossings where one line of track crosses another line.

The general object of this invention is to provide a railway crossing so constructed that noise due to the passage of trains over the crossing will be reduced to a minimum and so constructed that a practically continuous and unbroken rail surface is provided for a car going in either direction, thus eliminating this breaking down and crushing of the rail ends and eliminating the consequent noise.

A further object is to provide vertically movable filler members at the intersection 25 of the rails which are automatically raised, as a car approaches upon either track and which fill up the spaces between the rail sections of the track on which the car is moving and provide improved and very simple means for shifting the filler members.

30 In many cities third rails are provided for cars having a wider engage than ordinary cars and another object is to provide means whereby the spaces at the intersection of these third rails may be automatically filled up as the car approaches.

Other objects will appear in the course of the following description.

My invention is illustrated in the accompanying drawings, wherein,

Figure 1 is a top plan view of a crossing constructed in accordance with my invention;

Fig. 2 is a section on the line 2-2 of

45 Fig. 1;

Fig. 3 is a section on the line 3-3 of Fig. 1;

Fig. 4 is a section on the line 4-4 of Fig. 1; and

50 Fig. 5 is a section on the line 5-5 of Fig. 1;

Fig. 6 is a side elevation of one of the slide bars showing a modified form thereof.

Referring now particularly to Fig. 1, it will be seen that I have illustrated a crossing consisting of two lines of track inter-

secting each other at right angles. The sections forming one rail are designated 10, 10^a, 10^b and 10^c. The sections forming the other rail of the same track are designated 11, 11^a, 11^b and 11^c. The sections forming one rail of the crossing track are designated 12, 12^a and 12^b. The parallel rail sections are designated 13, 13^a and 13^b and the third rail sections are designated 14, 14^a and 14^b. These rails are illustrated as ordinary T rails, but it is obvious that other forms of rails may be used.

Disposed in the center of the crossing, is a box or casing designated generally 15, which is square so that its side walls 16 confront the rails 10, 11, 12^a and 13^a, but are spaced from the inside edges of these rails. Disposed parallel to the rails 10 and 11, 10^a and 11^a, 10^b and 11^b, are the walls 17. These walls are spaced from the inside edges of the rails and held in this spaced relation by means of spacing members of any suitable character, these spacing members being illustrated in Figs. 2 and 3 and designated 18. Like walls 17^a are disposed in spaced relation to the inside faces of the rails 12 and 12^b, 13 and 13^b, 14, 14^a and 14^b, and like spacing members are used to space these walls from the rails.

85 All of the rails on their inside faces are provided with the filling blocks 19 illustrated in Figs. 4 and 5, the outer faces of these filling blocks coming flush with the outer faces of the rail heads and the spacing members 18 and the walls 15 and 17, being held in proper cooperative relation to the rails by means of bolts 20, as shown in Figs. 4 and 5. Disposed between each of the walls 17 and the adjacent ends of the parallel rails are the vertically movable filler blocks 21. It will be seen that in the construction illustrated, having three rails running in one direction and two rails running in another direction, there are twelve of

100 these vertically movable filler blocks. Each block, as illustrated in Fig. 3, is provided upon its inside face with a rib 22 which engages with a groove 23 formed in the adjacent face of the wall 17. It will be noted from Figs. 2 and 3 that the filler blocks 21 that are used on one line of rails are longer than the filler blocks used on the other line of rails for a reason which will appear later.

105 For the purpose of automatically raising these filler blocks, as a car approaches a crossing, I provide the trip members 24, one

of which is illustrated in Fig. 2, these trip members being disposed between the adjacent wall 17 and one of the rails and being pivoted at 25. The upper face of the trip member is so formed that under normal circumstances the trip member is disposed in the path of movement of the flange of the car wheel and the free end of the trip member is formed with a finger 26. Co-acting 5 with the trip member is a cam-like member 27 which is pivoted upon a bolt 28, as illustrated in Fig. 2 and which has rounded side faces 29 and 30. The rounded end of the finger 26 co-acts with the rounded surface 10 29 so that when the trip 24 is depressed, it will rotate the cam member 27.

Mounted to slide upon the supporting bar 31 is an actuating rod 32 having a beveled end 33 with which the rounded face 30 of 15 the member 27 is adapted to engage. This actuating bar 32 which constitutes a slide is provided with a plurality of wedges 34, whose inclined faces 35 are adapted to engage with the filler blocks 21 when the 20 slide bar 32 is shifted in one direction so as to cause the raising of the blocks. When the slide bar is shifted in the other direction, however, the blocks will fall. A pivoted lid or cover plate 36 is mounted between the rail and the adjacent wall 17 with 25 its free end normally resting upon the upper end of the member 27 and extending over the finger 26. When the trip 24 is raised, this pivoted cover 36 is also raised, as illustrated in dotted lines in Fig. 2. This pivoted cover prevents dirt from falling into the space between the walls 17 and the filler block 19. It will be noted that each of the 30 blocks 21 on its face adjacent the beveled end of the corresponding webs 34 is rounded, as at 37, so as to coat with the beveled face 35. Each of the slide bars 32 intermediate its ends, is formed with an offset 38 for engagement by an arm 39. There are four of 35 these arms 39 braced to shift together and mounted upon a vertical pivot 40. These arms are disposed within the rectangular casing 15 and each of the four walls 16 is slotted, as illustrated in dotted lines in Fig. 40 1 to permit movement of the arms, the ends of said arms projecting through these slots and engaging with the offset portion 38 of the corresponding slide bar.

As before remarked, it is necessary that 45 the slide bars 32, which extend parallel to one line of track, shall be disposed at a higher level than the slide bars 32, which extend parallel to the opposite line of track, so that one set of slide bars will pass beneath 50 the other set. Hence, it is necessary that the blocks 21, which coat with one set of slide bars shall be longer than the blocks which coat with the other set of slide bars. In Fig. 2, one set of blocks 21 is depressed 55 and in Fig. 3 the other set of blocks 21 is

shown as raised. When these blocks 21 are raised, it will be seen that they will fill up the spaces between the ends of the track sections and provide a continuous track surface. Thus, for instance, in Fig. 1 the blocks 70 21 which coat with the rail sections 10, 10^a, 10^b and 10^c and 11, 11^a, 11^b and 11^c are all shown as depressed, while the blocks 21 which coat with the rail sections 12, 12^a, 12^b, 13, 13^a, 75 13^b and 14, 14^a, and 14^b are all shown as raised, so that a car passing in the direction of the arrow on the track A has a practically continuous rail surface to travel over. Now, if a car approaches the crossing in the direction of the arrow B, in Fig. 1, the wheel flange will automatically strike the trip 24, adjacent the rail section 11 and the depression of this trip will cause the depression of the blocks 21 corresponding to the rail sections 12, 12^a, 12^b, 13, 13^a, 13^b, and 14, 14^a, 80 14^b and the shifting of the slide bar 32 actuated by the trip 24 for the section 11 shifts the arms 39 so as to shift the transversely extending slide bars 32 and cause the raising of the filling blocks coacting with the track sections 10, 10^a, 10^b and 10^c and 90 11, 11^a, 11^b and 11^c.

For the purpose of actuating the filler blocks 21 which are adapted to connect the track sections 11^b, 11^c and 10^b, 10^c, I provide 95 a lever 41 pivoted at 42, one end of which is engaged by an offset 43 on the slide bar 32 which extends parallel to the rail sections 13, 13^a and 13^b. The other end of this lever 41 engages with an offset 44 mounted upon 100 the slide bar 32 which extends parallel to the rail sections 14, 14^a and 14^b, and raises the filling blocks 21 which are designed to fill up the spaces between the sections 11^b, 11^c, 10^b and 10^c or permits them to fall. 105

The operation of my invention will be evident from what has gone before. When a car approaches in the direction of the arrow on track B, it approaches the proper trip so that all of the filler blocks 21 which 110 are designed to provide a continuous track for the car, in the direction of the arrow B, will be raised and the remainder of the filler blocks lowered. On the other hand, when the car approaches in the direction of the arrow A, the filler blocks between the sections 12, 12^a, 12^b, 13, 13^a, 13^b and 14, 14^a 115 and 14^b will be raised, while the remainder of the filler blocks are lowered. In Fig. 1, I have not illustrated the spacing members 120 18 or any means for housing the sliding bars 32, as this would tend to confuse the illustration. These members 18, however, are fully illustrated in Figs. 2, 3, 4 and 5. While I have illustrated a construction 125 which is particularly practical and which may be relatively cheaply made of standard materials, I wish it understood that various modifications might be made in the details of constructions, without departing from the 130

scope of the invention, thus the slide bars 32 may be modified as illustrated in Fig. 6 wherein the wedges are illustrated as formed in one piece with the slide bar by merely 5 cutting out the slide bar. In this figure the slide bar is designated 32^a, the wedge faces 35^a and the filling blocks 21^a. As also illustrated in this figure the slide bars may be made in sections formed with scarfed 10 ends 45 to provide the opening for the extremity of the member 39^a, the two sections of the slide being held in engagement with each other by bolts 46. I regard the construction illustrated in Fig. 6 as preferable 15 as there is no danger of the wedges becoming detached and it is more cheaply made.

Having thus described this invention, what is claimed is:—

1. In a street railway crossing, intersecting rails, two sets of vertically movable filler blocks disposed at the intersection of the rails, slide bars extending parallel to each rail, and having wedging members mounted thereon engageable with the respective filler 20 blocks, a rotatable member having radiating arms each engaged with one of the slide bars, and car wheel operated means disposed between one rail of each line of track and operatively connected to one of said slide 25 bars for shifting the connected slide bar, shifting said rotatable member, and operating the remainder of the slide bars.

2. In a street railway crossing, two lines of track extending at right angles to each 30 other, each line having rail sections disposed in spaced relation to each other, at the intersection of the tracks of the rails, walls extending parallel to each of said track sections, filler blocks mounted between each of 35 said walls and the adjacent track section, there being two sets of filler blocks, one for each line of rails, slide bars extending parallel to each rail and having wedging members carried thereby and engageable 40 with the filler blocks, a rotatable four-armed member disposed between the two lines of track, each arm being engaged with one of said slide bars, and car-operated means disposed adjacent to a rail of each line of track 45 and operatively engaged with a corresponding slide bar to shift the slide bar and thereby shift the rotatable member to cause a movement of one set of slide bars to a retracted position, thereby permitting the depression of the corresponding filler blocks and move the other set of slide bars to a projected position, to thereby cause the projection of the corresponding filler blocks. 50

3. In a street railway crossing, two lines 60 of track extending at right angles to each other, each line having rail sections disposed in spaced relation to each other, at

the intersection of the tracks of the rails, walls extending parallel to each of said track sections, filler blocks mounted between each of said walls and the adjacent track section, there being two sets of filler blocks, one for each line of rails, slide bars extending parallel to each rail and having wedging members carried thereby and engageable with the filler blocks, a rotatable four-armed member disposed between the two lines of track, each arm being engaged with one of said slide bars, car-operated means disposed adjacent to a rail of each line of track and operatively engaged with a corresponding slide bar to shift the slide bar and thereby shift the rotatable member to cause a movement of one set of slide bars to a retracted position, and thereby 65 permit the depression of the corresponding filler blocks and move the other set of slide bars to a projected position to thereby cause the projection of the corresponding filler blocks, a third rail extending parallel to one 70 of said pairs of rails and formed in sections, filler blocks disposed at the ends of and parallel to said sections, a slide bar having wedges engaging said filler blocks when the slide bar is moved in one direction, to thereby 75 raise the filler blocks, and a lever operatively connecting the last named slide bar with the next adjacent parallel slide bar of the next adjacent parallel rail.

4. In a street railway crossing, a plurality 80 of rail sections spaced from each other, walls extending parallel to but spaced from the rail sections, vertically movable filler blocks disposed between the ends of the rail sections and said walls, a longitudinally 85 movable slide bar operatively supported beneath the filler blocks and carrying wedges engageable with the filler blocks to raise them when the slide bar is moved in one direction, a trip member pivoted at the side of one of 90 said rail sections, and depressible by engagement with the flange of a car wheel, a pivotally mounted member having rounded faces, and disposed in a vertical plane, one 95 of the rounded faces engaging with the adjacent end of the corresponding slide bar, the other being adapted to be engaged by the extremity of the depressible trip member, and a pivoted cover disposed above the 100 slide bar and normally resting upon the pivoted member and having its extremity 105 projecting over the trip member.

In testimony whereof I hereunto affix my signature in the presence of two witnesses.

HENRY B. COLE.
